Be it known that I, ALFRED J. MANNING, of the city, county, and State of New York, have invented and produced a new Design for the Backs of Playing-Cards, of which the following is the specification:

card, consisting of a cluster of thistles, A, substantially as shown and described.

2. The design for the back of a playing-card, consisting of the cluster of thistles A and surrounding leaves B, substantially as set forth.

In testimony whereof I have signed my name to this specification in the presence of two subscribing witnesses.

ALFRED J. MANNING.
